(57) **CLAIM**

The design for a bucket for excavator, as shown and described.

DESCRIPTION

FIG. 1 is a left, side view of a bucket for excavator showing my new design, the right side is substantially a mirror image; FIG. 2 is a front and right side perspective view thereof; FIG. 3 is a rear and right side perspective view thereof; and, FIG. 4 is a rear and right side perspective view from a different angle.

The broken line showing is for illustrative purposes only and forms no part of the claimed design.
